COMBINED CYLINDER HEAD STAND AND
VALVE SPRING COMPRESSOR

Alvis W. Taylor, Clovis, N. Mex.

Application January 17, 1949, Serial No. 71,294

5 Claims. (Cl. 29—219)

1

My invention relates to improvements in combined cylinder head stands and valve spring compressors for use in removing overhead valves in internal combustion engines.

The primary object of the invention is to provide a simply constructed device for supporting the cylinder heads of overhead valve engines, with the valves held seated in a manner to facilitate compressing of the valve springs and removal of the spring retaining devices quickly and easily so that the valves may be removed with a minimum of labor.

Another object is to provide a device of the character and for the purpose set forth which is especially adapted for performing such operations in the removing of valves of either six or eight cylinder overhead valve engines in which the cylinders are arranged in line.

Still another object is to provide a device for the purposes above set forth which is inexpensive to manufacture and install and will not get out of order under prolonged use.

Other and subordinate objects, within the purview of my invention, together with the precise nature of my improvements will be readily understood when the succeeding description and claims are read with reference to the drawings accompanying and forming part of this specification.

In the said drawing:

Figure 1 is a view in perspective of my invention in the preferred embodiment thereof with a cylinder head supported thereby and shown in broken lines;

Figure 2 is a view in plan partly broken away;

Figure 3 is a view in longitudinal vertical section taken on a line 3—3 of Figure 2;

Figure 4 is a view in vertical transverse section taken on the line 4—4 of Figure 1;

Figure 5 is a fragmentary view in perspective of the spring compressing plunger drawn to a larger scale;

Figure 6 is a fragmentary view in vertical section of one of the valve rests;

Figure 7 is a view in perspective of one of the pair of cylinder head elevating blocks;

Figure 8 is a fragmentary view in transverse section illustrating the use of one of the cylinder head elevating blocks.

Referring now to the drawings by numerals, the stand of my invention, as illustrated, comprises an open front, rectangular cabinet 1, of any suitable material, preferably sheet metal, with ends 2, a back 3, a bottom 4 and a flat top 5 extending beyond the right hand end 2 of the cabinet for 55

2

a purpose presently seen. A longitudinal slot 6 in the top 5 extends between the ends 2 in the rear of the longitudinal center of the top 6 for a particular purpose presently apparent. The slot 6 corresponds in length, substantially, with that of the head of an eight cylinder overhead valve engine. The top 5 is designed to support thereon a cylinder head H shown in dotted lines in Figure 1 over and aligned with the slots 6, it being understood that the said slot is narrower than the said head.

A vertically slidable, upright valve supporting frame 7 is provided in the cabinet 1 in vertical alignment with the slot 6 and comprising end 15 guide sleeves 8 vertically slidable on upright guide rods 9 spaced beyond the ends of the slot 6 and having flanged ends 10 bolted, as at 11, to the top 6 and bottom 10. A horizontal lower rod 12, and a similar upper rod 13 rigidly connect said 20 guide sleeves 8 and complete the frame 7. Tubular posts 14 with enlarged, square, flat head 15 thereon are suitably fixed at the lower ends thereof on spacing sleeves 16 on the lower rod 12, said sleeves being held in end to end engagement by cotter pins 17 in said rod 12. The upper rod 13 extends through the tubular posts 14 to hold the same rigidly in the frame 7. The heads 15 form valve rests, or supports, as will presently more clearly appear. For this purpose, the 25 posts 14 are spaced apart along the frame 7 in correspondence with the spacing of valves 18 in the cylinder head H so that the heads 15 will properly function as valve rests or supports.

The posts 14 as shown, and the heads 15 are 30 of the requisite number for supporting valves 18 in the head of the six cylinder engine, but, the frame 7 is of sufficient length so that other posts 14, and heads 15, may be added for the valves of a cylinder head for an eight cylinder overhead 35 valve engine. This may be accomplished by having the upper and lower rods 13, 12 detachable, in any suitable manner, not shown, from the guide sleeves 8.

The posts 14, sleeves 16 and the guide sleeves 45 8, for economy in costs of construction, may take the form of stock pipe sections, and the heads 15, for further economy in construction, and for replacement purposes, may be secured on the upper ends of the posts 14 by nuts 19 threaded on the 50 said posts and on which said heads 15 are welded as at 20.

A vertically rocking U-shaped yoke 25 in the cabinet 1 is pivoted at its sides, as at 26, on angle brackets 27, bolted as at 28, on the bottom 4 of 55 said cabinet. Flat end plates 29 on said yoke 25

are suitably slotted, as at 30, for extension of the guide rods 9 therethrough so that said plates 29 underlie the lower ends of the guide sleeves 8 whereby the yoke 25 may be rocked in a direction to lift said sleeves 8 and adjust the frame 7 upwardly to move the heads 15 through the slots 6 against the valves 18 to act as supports or rests for maintaining said valves closed while the valve springs and spring retaining devices are being removed. The yoke 25 may be economically formed of tubular stock with flat ends 33 on which the plates 29 are suitably welded, as at 33'. A foot pedal 31 extends from the center of the yoke 25 out of the center of the cabinet 1 for rocking the yoke 25 so as to lift the frame 7.

A yoke locking rod 34 extends upwardly from the yoke 25 through a suitable opening 35 in the top 5 and is fixed at its lower end on a rotatable sleeve 36 on said yoke and provided with longitudinally spaced notches 37 so that said rod may be swung to engage a selected notch over the edge of the opening 35 to lock the yoke 25 after the frame 7 has been lifted to proper position. As will be understood, the yoke 25 may be rocked to lower the plates 29 so that the frame 7 will drop to a lowered position and into the cabinet 1 below the top thereof when the device is not in use.

A coil spring 38 fixed at one end, as at 39 in the cabinet 1 with its other end suitably fixed to a collar 40 on the yoke locking rod 34 urges said rod into a position to engage the notches 37 with the edge of the opening 35. A set screw 41 suitably engages the yoke 25 and is extended through the sleeve 36 to prevent said sleeve from creeping along the yoke 25 during rocking of said yoke. A suitable hand grip 42 is provided on the yoke locking rod 34.

A tubular frame 43 of inverted U-shape is provided at the back of the cabinet 1 and has its sides 44 vertically slidably in tubular guides 45 arranged at the rear corners of the cabinet 1 so that said frame 43 extends at its top along and above the top 5 of the cabinet. The lower ends of the guides 45 are welded, as at 46, to the bottom 4 of the cabinet 1 and extend upwardly through the top 5 for a short distance to fix the said guides in said top. Set screws 47 in said guides 45, above the top 5, provide for setting said frame 43 in vertically adjusted positions for a purpose presently apparent.

A rod-like hand lever 48 is provided to extend forwardly of the frame 43 above the cylinder head H and is mounted on said frame for vertical swinging and lateral sliding adjustment along said frame by means of a sleeve 49 to which said lever is attached at one end and which is rotatable and slidable along the top of the frame 43.

A plunger 50 for compressing the valve springs, one of which is shown at 51 in broken lines, is pivoted at its upper end, as at 52, on a clip 53 on said lever 48 and provided with a bifurcated, right angled, foot 54 welded to its lower end, as at 55, the arrangement being such that said lever 48 is vertically swingable and laterally adjustable along the frame 43 so as to position the foot 54 for manual swinging on the pivot 52 into straddling relation to the stem of a selected valve 18 and in overlying position to the spring 51 on the said valve.

As will now be seen, with the frame 7 adjusted in the manner described so that the heads 15 support the valves 18 seated, the hand lever 48 may be adjusted vertically and laterally so that

the plunger 50 may be manually swung to position the foot 54 in the manner described relative to the stem and spring of a selected valve 18. The hand lever 48 may then be swung downwardly to cause the foot 54 to compress the selected valve spring 51 so that the spring retaining devices may be detached, in the usual manner, and the valve spring then removed so that the valve 18 may subsequently be removed.

The top 5 is provided adjacent the slot 6 with suitable openings 57 for receiving dowel pins 58 on a pair of blocks 59 adapted to be anchored on the top 5 by said pins 58 and openings 57 to support the head H elevated on the top 5 in inverted position for removing the valves 18 or reseating the same.

At the right hand end of the top 5, which extends past the adjacent end 2 of the cabinet 1, rows of openings 59' are provided in said top for the insertion of the stems of the removed valves 18 therein in associated pairs in an out-of-the-way position as regards an operator working in front of the cabinet.

Corner casters 60 on the cabinet 1 provide for wheeling the same about, as desired, for instance to a valve refacing machine where the valves in the openings 59 may be removed conveniently for refacing operations.

The foregoing will, it is believed, suffice to impart a clear understanding of my invention, without further explanation.

Manifestly, the invention, as described, is susceptible of modification without departing from the inventive concept, and right is herein reserved for such modifications as fall within the scope of the appended claims.

Having described the invention, what is claimed as new is:

1. A combined cylinder head stand and valve spring compressor comprising a cabinet having a top provided with an elongated slot therein for supporting a cylinder head with the valves disposed over the slot, a vertically movable frame in said cabinet, separate supports for the valves mounted on said frame for vertical movement thereby out of said cabinet and slot into supporting relation to said valves, manipulative means for moving said frame, and manipulative means for compressing the valve springs.

2. A combined cylinder head stand and valve compressor comprising a cabinet having a top provided with an elongated slot therein for supporting a cylinder head with the valves disposed over said slot, a vertically movable frame in said cabinet, supports for said valves mounted on said frame and movable thereby out of said cabinet and slot into supporting relation to said valves, manipulative means for moving said frame, manipulative means for compressing the valve springs preparatory to removing the same, and blocks for positioning over said slots to hold the head elevated off said top to facilitate valve seating operations after the springs have been removed.

3. A combined cylinder head stand and valve spring compressor comprising a cabinet having a top provided with an elongated slot therein for supporting a cylinder head with the valves disposed over the slot, a vertically movable frame in said cabinet, separate supports for the valves mounted on said frame for vertical movement thereby out of said cabinet and slot into supporting relation to said valves, manipulative means for moving said frame, and manipulative means for compressing the valve springs, the

70
75

first mentioned means comprising a rocking yoke in said cabinet operatively connected to said frame, and a foot pedal on said yoke extending out of said cabinet for rocking said yoke.

4. A combined cylinder head stand and valve spring compressor comprising a cabinet having a top provided with an elongated slot therein for supporting a cylinder head with the valves disposed over the slot, a vertically movable frame in said cabinet, separate supports for the valves mounted on said frame for vertical movement thereby out of said cabinet and slot into supporting relation to said valves, manipulative means for moving said frame, and manipulative means for compressing the valve springs, the last mentioned means comprising a vertically adjustable frame upstanding above said top and extending along said top, and a hand lever laterally shiftable along said last mentioned frame and vertically swingable thereon with a pivoted plunger depending therefrom and swingable thereon for engaging the valve springs selectively.

5. A combined cylinder head stand and valve spring compressor comprising a cabinet having a top provided with an elongated slot therein for supporting a cylinder head with the valves disposed over the slot, a vertically movable frame in said cabinet, separate supports for the valves

15

20

25

mounted on said frame for vertical movement thereby out of said cabinet and slot into supporting relation to said valves, manipulative means for moving said frame, and manipulative means for compressing the valve springs, the first mentioned means comprising a rocking yoke in said cabinet operatively connected to said frame, a foot pedal on said yoke extending out of said cabinet for rocking said yoke and spring tensioned means for locking said yoke to hold said frame stationary after the supports have been moved into valve supporting position.
